UNITED STATES PATENT OFFICE.

JAMES K. DAVIS, OF CHESTER, NEW JERSEY.

EXTENSION-STEP.

1,315,933.

Specification of Letters Patent. Patented Sept. 9, 1919.

Application filed November 12, 1918. Serial No. 262,214.

To all whom it may concern:

Be it known that I, JAMES K. DAVIS, a citizen of the United States, residing at Chester, in the county of Morris and State of New Jersey, have invented certain new and useful Improvements in Extension-Steps, of which the following is a specification.

This invention has relation to steps for cars and other types of public carriers and vehicles generally wherein the steps have an extension which may be projected into operative position or folded when not required for immediate service thereby reducing the length of the steps so as to avoid their coming in contact with an object.

The invention relates more particularly to the means whereby the extension step is connected to the main step and is braced when extended so as to sustain the weight and strain to which the step will be subjected when in service.

The invention has for its object to combine with the extension step novel locking means for securing the step in folded position, said locking means being disposed for convenience of manipulation and so as to be out of the way when the step is extended or folded.

The invention furthermore aims to provide novel connecting means between the extension step and the main steps which are self locking when the extension step is projected and which are operable when the extension step is folded thereby enabling the operation to be performed by one hand.

The drawing illustrates a preferred embodiment of the invention. However, it is to be understood that in adapting the same to meet different conditions, various changes in the form, proportion, and minor details of construction may be resorted to without departing from the nature of the invention as claimed hereinafter.

Referring to the accompanying drawings:

Figure 1 is a perspective view of an extension step embodying the invention.

Fig. 2 is a detail view of the step as seen from below, the side pieces being in section to show more clearly the engagement therewith of the locking elements.

Fig. 3 is a sectional detail showing the relation of the parts when the extension step is in folded position, and

Fig. 4 is a view similar to Fig. 3 showing the relation of the parts when the ex-

tension step is projected into operative position.

Corresponding and like parts are referred to in the following description and indicated in the several views of the drawing by like reference characters.

The main steps are of usual construction and comprise side pieces 1 and treads 2. The extension step 3 is connected to the lowermost tread of the main steps so as to fold beneath the lowermost tread thereof as indicated most clearly in Fig. 3. A plurality of connecting means are utilized for attaching the extension step to the lowermost tread of the main steps and each of these means embodies a lock joint so as to hold the extension step in horizontal position when projected. The connecting means embodies a folding brace and hinge members. The folding brace is centrally disposed whereas the hinge members are located at or near the ends of the extension step. The folding brace comprises complementary members 4 and 5 which are connected by means of a rule joint 6 so as to hold the extension step projected against any possible displacement when in active position. The folding brace is connected to the step in any manner and preferably is provided at its ends with straps 7 which are secured to the under side of the extension step 3 and the lowermost tread of the main steps. On reference to Fig. 4, it will be observed that the pivot connection 8 between the folding brace and the extension step 3 is disposed about in line with the lower rear corner of the extension step and this is of advantage as will appear more fully hereinafter.

The hinge connections between the extension step and the main steps are duplicates; hence a detailed description of one will suffice for a full understanding of both. Each hinge connection comprises members 9 and 10 which are hingedly connected at 11 in any manner and each member is provided with an oblique extension 12 and 13 respectively. The extensions 12 and 13 are disposed to abut when the extension step 3 is lowered into operative position as indicated most clearly in Fig. 4. The extensions 12 and 13 are of sufficient length to insure a bracing connection and to limit the relative unfolding of the extension step. The hinge joint 11 is disposed at the upper rear corner of the extension step as indicated most

clearly in Fig. 4. As a result of the disposition of the hinge joints 8 and 11, the extension step when in the act of folding will have its rear edge come in contact with the 5 member 5 of the folding brace and a continued movement of the extension step in the act of folding will break the joints between the members 4 and 5 of the folding brace and admit of the step 3 folding so as 10 to underlie the lowermost tread of the main steps as indicated most clearly in Fig. 3. It will thus be understood that it is not necessary to employ one hand to break the joints between the members of the folding brace 15 when it is required to fold the extension step since such result is automatically brought about by the contact of the extension step with the member 5 of the folding brace in the manner stated. The extensions 12 and 20 13 of the respective members 9 and 10 constitute integral portions of such members.

When the extension step is folded, it is made secure by locking means, the same comprising oppositely disposed bars 14 and 25 15 and an operating bar 16, the latter being pivoted intermediate of its ends as indicated at 17. The operating bar 16 is provided at its forward end with a finger piece 18 for convenience of manipulating the locking 30 means. It is preferred not to have the operating bar project beyond the forward edge of the step 3. The locking bars 14 and 15 are retained in place in any preferred manner and as indicated keepers 19 are applied 35 to the step 3 and receive the locking bars. The outer ends of the locking bars are adapted to engage the side pieces 1 of the main steps and for this purpose said side pieces project a short distance below the 40 lowermost tread and have recesses 20 formed in their inner faces to receive the projecting ends of the locking bars as shown most clearly in Fig. 2.

When extension step 3 is in folded position, it underlies the lowermost tread of the main steps and is retained in place by the locking means herein indicated. When the extension step is projected in the operative position, it appears substantially as indicated in Figs. 1 and 4. Downward movement of the extension step is prevented by the abutting of the oblique extensions 12 and 13 and rearward movement of the extension step is prevented by the folding brace. The 50 55 folding brace breaks joint by a rearward movement; hence when folding the extension

step the latter is elevated at its forward end and when reaching a position about at a right angle to the length of the folding brace, the rear edge of the extension step 60 comes in contact with the member 5 and a continued movement of the extension step breaks the joint of the folding brace thereby admitting of the extension step folding into closed position when it is made secure by 65 the locking means in the manner set forth.

The foregoing description and the drawings have reference to what may be considered the preferred or approved form of my invention. It is to be understood that I 70 may make such changes in construction and arrangement and combination of parts, materials, dimensions, etc., as may prove expedient and fall within the scope of the appended claims.

Having thus described the invention, what I claim as new and desire to secure by Letters Patent, is:—

1. In combination with main and extension steps, a member pivoted to the main 80 steps and having a rear oblique extension at its lower end, a member secured to the extension step and pivoted to the pivoted member and having an oblique extension at its rear end to coact with the oblique extension of the 85 pivoted member to hold the extension step projected, and a folding brace comprising members connected by means of a rule joint and pivotally connected to the steps and adapted to have the rule joint broken by the 90 extension step when folding it.

2. In combination with main and extension steps, a member pivoted to the forward edge of the lowest tread of the main steps and having a rear oblique extension at its 95 lower end, a member connected to the extension step and pivoted to the pivoted member and having an oblique extension at its rear to coact with the oblique extension of the pivoted member and a folding brace 100 pivoted to the rear of the lower tread of the main steps and to the rear of the extension steps and connected by means of a rule joint which is adapted to break rearward and downward automatically by the action of the 105 extension step when folding it.

In testimony whereof I affix my signature in presence of two witnesses.

JAMES K. DAVIS.
